UNITED STATES PATENT OFFICE.

DELL WARD, OF GRAND RAPIDS, MICHIGAN, ASSIGNOR OF ONE-HALF TO
JOSEPH R. TAYLOR, OF GRAND RAPIDS, MICHIGAN.

FLASH-LIGHT GAS-BURNER.

SPECIFICATION forming part of Letters Patent No. 695,014, dated March 11, 1902.

Application filed November 14, 1901. Serial No. 82,316. (No model.)

To all whom it may concern:

Be it known that I, DELL WARD, a citizen of the United States, residing at Grand Rapids, in the county of Kent and State of Michigan, have invented a new and useful Flash-Light Gas-Burner, of which the following is a specification.

My invention is an improved automatically-operating flash-light gas-burner especially adapted for illuminating glass signs and for analogous uses; and it consists in the peculiar construction and combination of devices hereinafter fully set forth and claimed.

In the accompanying drawings, Figure 1 is a sectional view of an automatically-operating flash-light gas-burner constructed in accordance with my invention. Fig. 2 is a similar view showing a modification.

In carrying out my invention I employ an expansible gas-holder 1, which may be of any suitable construction and is here shown as comprising a water-seal chamber 2 and a vertically-movable bell 3, the lower side of which is disposed in said water-seal chamber. A gas-pipe 4, which extends upwardly in the gas-holder from the bottom thereof, is adapted to supply gas to the gas-holder from any suitable source.

The bell 3 or vertically-movable member of the gas-holder is here shown as provided with a burner 5, which communicates with an opening 6 in the upper end of the bell. A valve 7 is provided, which in coaction with the said opening regulates the escape of gas from the gas-holder. The valve is here shown as hinged at one end under the top of the movable element of the gas-holder, as at 8, and as being disposed to cover the opening 6, as shown in Fig. 1. A guide 9 depends from the upper side of the bell or movable element of the gas-holder and limits the movement of the said valve. In the form of my invention shown in Fig. 1 the valve 7 is provided with an orifice 10 of slight diameter to constantly supply the tip of the burner with a small quantity of gas, so that a small flame may be kept constantly burning for the purpose of igniting the larger volumes of gas consumed intermittently by the operation of the burner in the production of the flash-lights. An operating-rod 11 is connected to and depends

from the valve 7. The said rod is of suitable length to reach the bottom of the water-seal chamber 2 when the bell or movable element of the gas-holder is at the lower limit of its movement, the bottom of the said chamber 2 forming a stop, which coacting with the rod 11 causes the valve to close the opening 6 at the end of the downstroke of the bell or movable element of the gas-holder. As here shown the lower portion of the rod 11 operates in a guide 12, which projects from one side of the gas-supply pipe 4, and the lower end of said rod 11 is bent to form a trip-arm 13, which, in coaction with said guide 12, which also forms a stop by arresting the ascent of the rod 11 near the limit of the upstroke of the bell or movable element of the gas-holder, causes said rod to open the valve 7, and thereby permit the gas accumulated in the gas-holder to be fed to the burner 5 and burned brilliantly, creating a flashing light which endures during the descent of the bell or movable element of the gas-holder.

It will be understood that the pressure of the gas under the bell or movable element of the gas-holder will keep the valve 7 closed and cause the said bell to rise until the trip 13 of the rod 11 by engaging the guide and stop 12 opens said valve, as hereinbefore described. As the gas is being supplied to the burner during the downstroke of the bell the pressure thereof on the valve is diminished and the weight of the valve, together with that of its operating-rod 11, keeps the valve open during the descent of the bell and while the flashing light is burning.

In the modified form of my invention shown in Fig. 2 the gas-pipe 4 is provided with a by-pass, here shown as a pipe 14 of diminished diameter, which leads to an igniting constantly-burning burner 15, disposed in such relation to the burner 5 as to ignite the gas, which escapes from the latter intermittently by the automatic operation of my improved burner.

I do not desire to limit myself to the precise construction and combination of devices herein shown and described, as it is evident that modifications may be made therein without departing from the spirit of my invention.

In practice I provide the seal-chamber with vertical guides 16, which project from the upper end thereof, and provide the upper end of the bell 3 with a stop, here shown as a transversely-disposed bar 17, the ends of which operate in said guides. Said guides and stop limit the ascent of the bell.

Having thus described my invention, I claim—

- 10 1. An intermittently-acting gas-burner comprising a gas-holder having an element movable in one direction by the pressure of the gas therein, said movable element having a gas-escape passage, a valve, carried by said movable element, to close said gas-escape passage and maintained in closed position by the pressure of the gas during the outstroke of said movable element, and a connection between said valve and a fixed point to open 15 said valve at the limit of the outstroke of said movable element, substantially as described.
- 15 2. In a gas-burner of the class described, the combination of an expansible gas-holder having means to supply gas thereto, the movable element of said holder having a gas-escape passage, a valve pivotally connected to and carried by said movable element and actuated by the pressure of the gas to close said passage during the outstroke of said element, 20 and means to open said valve at the limit of the outstroke of said movable element, substantially as described.
- 25 3. In a gas-burner of the class described, the combination of an expansible gas-holder, having an element movable in one direction by the pressure of the gas therein, said movable element having a gas-escape passage, a valve to open and close said passage, said valve being movable with said movable element and maintained in closed position by 30

the pressure of the gas during the outstroke of said movable element, and means to open said valve at the limit of the outstroke of said movable element and close said valve at the limit of the reverse stroke of said movable element, substantially as described. 45

4. In a gas-burner of the class described, the combination of an expansible gas-holder, having an element movable in one direction by the pressure of gas therein, said movable 50 element having a gas-escape passage and a burner to which said passage leads, a valve to open and close said passage and maintained by the pressure of the gas in a closed position during the outstroke of said movable element, said valve having a gas-passage of reduced capacity therein, and means to close said valve at the limit of the instroke of said movable element, substantially as described. 55

5. In a gas-burner of the class described, the combination of an expansible gas-holder, having an element movable in one direction by the pressure of gas therein, said movable 60 element having a gas-escape passage, a valve, carried by said movable element, to open and close said gas-escape passage, an operating element connected to said valve and having a trip and fixed stops, alternately engaged by said trip, to open and close said valve at 65 the limits of the strokes of said movable element, substantially as described.

In testimony that I claim the foregoing as my own I have hereto affixed my signature in the presence of two witnesses.

DELL WARD.
